UNITED STATES PATENT OFFICE.

FREDERICK J. LINND, OF FALCONER, NEW YORK.

PADDLE-WHEEL.

1,305,727.

Specification of Letters Patent.

Patented June 3, 1919.

Application filed February 8, 1918. Serial No. 216,000.

To all whom it may concern:

Be it known that I, FREDERICK J. LINND, a citizen of the United States, residing at the village of Falconer, in the county of Chautauqua and State of New York, have invented certain new and useful Improvements in Paddle-Wheels, of which the following, taken in connection with the accompanying drawings, is a specification.

10 The invention relates to vessels and means for propelling the same; and the improvement consists in providing a simple yet strong paddle wheel mechanism in which the contour or propelling surface of each 15 paddle is progressively increased and diminished as said paddle wheel is turned around a fixed cylinder placed off center for the inner ends of the paddles or buckets which graduates the extension of said paddles so that they obtain a deep broad hold 20 on the water on the lower side of said cam-shaped boxing and are so slidably mounted as to recede into the wheel on the upper side of said cam-shaped boxing, thus giving the 25 desired strong propelling force upon the water and being largely out of the way during the upper portion of the rotation; and the invention consists in the novel features and combinations hereinafter set forth and 30 claimed.

In the drawings, Figure 1 is a an elevation of my paddle wheel with one-half of the paddle holding drum or box removed showing the construction and arrangement 35 of the paddles and the outer end of the fixed cylinder or cam-shaped boxing for the inner ends of said paddles with the connective chain for the paddle ends. Fig. 2 is an exterior end elevation of the paddle wheel. Fig. 40 3 is an elevation of the paddle wheel and the support therefor showing a portion of the support broken away and showing the support for said fixed cylinder for the paddle wheel. Fig. 4 is an edgewise view with the 45 outer half of the slotted paddle supporting drum on the shaft withdrawn from its normal position and showing the construction and arrangement of the different parts. Fig. 5 is a perspective view of a portion of the 50 fixed cylinder or cam-shaped boxing on the shaft with the chain extending over the same and one of the paddles or buckets attached to said chain in the radial extending position. Fig. 6 is an elevation of the fixed 55 cylinder or cam-shaped boxing support for the inner ends of the paddles. Fig. 7 is a

sectional view at line 7—7 in Fig. 1 showing the construction and arrangement of the different parts. Fig. 8 is a perspective view of one of the halves of the slotted paddle 60 supporting drum showing the interior thereof with the radial slots. Fig. 9 is an elevation of one of the paddles or buckets with the attaching link arm and rollers thereon. Fig. 10 is a side elevation of a portion of 65 the chain with the inner end of the link arm attached thereto midway of the length of a chain link and the inner end portion of one of the paddles attached to said arm. Fig. 11 is a plan view of the attaching spider 70 for the slotted paddle drum with the square end of the driving shaft in section therein.

Like characters of reference refer to corresponding parts in the several views.

The numeral 10 designates the shaft which 75 is supported in a suitable standard 11 having a fixed boxing 12 which boxing 12 has the cam-shaped or cylindrical enlargement or boxing 13 placed off center thereon. The cylindrical boxing 13 is round and smooth 80 on its outer surface, and placed toward the lower side of the wheel the distance which it is desired to extend or enlarge the paddle blades or buckets 16 of the paddle wheel as they pass through the water to thereby give 85 a larger resisting hold upon the water than would otherwise be attained.

A chain 14, preferably of the sprocket type, extends around the cylinder 13 and has pivotally attached thereto at spaced distances the link arms 15 which extend out therefrom and are pivotally attached to the paddle 16 at the outer end of the arm 15 90 preferably by means of a cross rod 17 which extends through a hole in arm 15 and is welded each side of a slot 18 through which the arm 15 freely passes backward and forward.

The paddle blade or bucket 16 besides its arm 15 and open ended slot 18 on its inner 100 end bears the two rollers 19 on rods 20 in openings, one each side of the slot 18 to bear against and roll freely upon the smooth cylinder 13, the rods 20 being welded to the blade 16 at each end. A track for the rollers 19 may be provided on said smooth cylinder 13 extending around the periphery thereof without departing from my invention.

The paddle blades 16 are normally held in spaced relation to one another and substantially radial by means of a slotted drum composed of two halves 21 and 22 which

are attached to one another by means of the bolts 23. The drum is rotatably mounted on the fixed boxing 13 on the shoulders 24, the drum being held in place 5 by means of the spider plate 25 which is attached on the squared end 26 of the shaft 10, being held against the shoulder 27 by means of the attaching nut 28 and bolted to the drum 21-22. It is now apparent that 10 the paddle wheel drum formed by the parts 21 and 22 will be revolved upon the fixed cylindrical portion of the box 12-13 on the bearings 24 by the turning of the shaft 10, the rollers 19 running freely upon the 15 outer surface of the cylinder 13 and the pivotally mounted arms or links 15 allowing the adaptation of the inner ends of the paddle blades 16 to the position of the different parts during the rotation of said 20 blades 16 and the chain 14 around the cylindrical boxing 13.

Each of the divisions 21 and 22 are provided with the correspondingly spaced open ended slots 29 which fit to one another 25 and extend radially having the inwardly extending flanged projections 30 each side of each slot 29 to form guide ways for the paddle blades 16 as they move outward and inward during rotation. The inwardly projecting spaced flanges 30 extending cross-wise of each half 21 and 22 meeting in the center around the inner periphery of the paddle wheel drum, said flanges 30 extending upon the inner end walls of the drum 35 nearly to the cylinder 13 when placed thereon.

In operation, the shaft 10 is rotated thereby turning the drum 21-22 with the paddle blades attached therein thereby rotating the chain 14 around the fixed cylinder or cam-shaped boxing 13 causing the rollers 19 on the inner ends of the paddle blades 16 to roll around the cylinder 13 thereby increasing the extension of said 45 paddle blades 16 through the slots 29 on the lower side of the drum 21-22 the distance which the cylinder 13 is set off center toward said lower side and withdrawing said blades 16 within the paddle drum 50 21-22 a substantially equal distance on the upper side thereby obtaining a large paddle or bucket surface on the lower side as they pass through the water and giving a greater grip or resistance to the paddle 55 wheel, and giving less resistance to the paddles on the upper side of the paddle wheel as they pass through the air. The arms 15 move the blades or paddles in and out of the drum 21-22, though said 60 arms are assisted by gravity.

The flexible chain 14 is provided to allow for change of stroke for the paddles

16 and for the constant change of form from wear and other causes in the drum 13. The cam shape of the drum 13 may 65 be changed without departing from my invention.

I claim as new:

1. A paddle wheel comprising a shaft, a cam shaped boxing for said shaft, a chain 70 movably mounted around said boxing, paddle blades attached to said chain in spaced relation with freedom of movement around said boxing, a drum in two parts attached to one another and to said shaft, said drum 75 having spaced open ended slots in each of said parts to coincide and form one slot when said parts are attached to one another to receive said paddle blades therethrough in radial alinement with said shaft. 80

2. A paddle wheel comprising a shaft, a fixed cylindrical boxing mounted off center for said shaft, a chain movably mounted around said fixed cylindrical boxing, paddle blades having slots in their inner ends 85 to receive said chain therethrough, arms pivotally attached to said chain at one end and to said blades at the other to permit said arms to move backward and forward through said slots, rollers on the inner ends of said blades to roll around said fixed cylinder, and a drum having radially spaced slots around the periphery thereof to receive said paddle blades therethrough in radial alinement with said shaft to give 90 an outward and inward movement to said paddle blades as they rotate around said off center boxing. 95

3. A paddle wheel comprising a shaft, a journal for said shaft consisting of a comparatively large cylinder mounted off center on said shaft toward its lower side, a chain rotatably mounted around the central portion of said cylinder, paddle blades having a central open ended slot on each 100 of their inner ends to receive said chain therein, a link arm pivotally attached at one end in said chain and at the other end to said paddle blades near the outer ends of said open ended slots to permit side-wise adjustment for the inner ends of said paddle blades, and a drum around said cylinder having spaced slots therein placed radially to hold said paddle blades in radial alinement with said shaft with freedom 105 of outward movement on the lower side and inward movement on the upper side of said shaft. 110

In testimony whereof I have affixed my signature in the presence of two witnesses. 120
